UNITED STATES PATENT OFFICE.

WILLIAM E. SMALL, OF DALLAS, TEXAS.

SILO-ANCHOR.

1,165,029.

Specification of Letters Patent. Patented Dec. 21, 1915.

Application filed December 3, 1914. Serial No. 875,363.

To all whom it may concern:

Be it known that I, WILLIAM E. SMALL, a citizen of the United States, residing at Dallas, in the county of Dallas and State of Texas, have invented a new and useful Silo-Anchor, of which the following is a specification.

The device forming the subject matter of this application is adapted to be employed 10 for guying, reinforcing and sustaining an upright structure of any sort such as a silo or stack, the device being of peculiar utility when used in connection with silos, although of general utility for the purposes herein- 15 after outlined.

One object of the invention is to provide a novel means for connecting the flexible elements or guys with the silo or other upright structure and with the ground engag- 20 ing anchors.

Another object of the invention is to pro- 25 vide a means whereby the upright structure will not only be sustained against tipping over but, as well, will be reinforced internally, to resist the strains resulting from the efforts of those elements which act as guys.

It is within the scope of the invention to 30 improve generally and to enhance the utility of devices of that type to which the present invention appertains.

With the above and other objects in view which will appear as the description pro- 35 ceeds, the invention resides in the combina- tion and arrangement of parts and in the details of construction hereinafter described and claimed, it being understood that changes in the precise embodiment of the invention herein disclosed can be made within the scope of what is claimed without de- 40 parting from the spirit of the invention.

In the accompanying drawing:—Figure 1 is a perspective view, in the nature of a dia- 45 gram, illustrating the means whereby the silo or other structure is sustained, the silo for the most part being broken away in order that the bracing means be clearly dis- closed; Fig. 2 is a horizontal section taken adjacent the top of the silo; Fig. 3 is a horizontal section taken midway between the up- 50 per and lower ends of the silo and disclosing particularly the lower, internal reinforcing band; Fig. 4 is a side elevation of the complete invention; Fig. 5 is a plan showing one of the eye bolts; Fig. 6 is a perspective 55 showing another of the eye bolts and attendant parts.

In the drawings there is shown an upright structure 1 which may be a stack, a silo or the like. To avoid prolixity and repetition it will be presupposed hereinafter, 60 without prejudice, that the invention herein disclosed is applied to a silo.

Located within the silo 1 adjacent the upper end thereof is a reinforcing ring or band denoted by the numeral 2 and extended entirely around the silo. The ring or band 2 may be made in two parts as clearly shown in Fig. 2. The constituent parts of the ring are overlapped at their ends and the overlapped ends are provided with a plurality 70 of openings 50 adapted to receive securing elements 51, the construction being such that the ring may be shaped properly to cooperate with silos of slightly different dimensions and particularly, to provide for the 75 expansion and contraction in any given silo. Upper holding devices are disposed opposite to each other and are extended through the wall of the silo 1 into engagement with the ring 2. These upper holding devices 80 may be of any desired form. In Fig. 5 they are shown as double eye bolts 3 carrying nuts 4 and washers 5 which may be made of lead. The washers 5 are crowded up closely against the ring 2 by the action of the nuts 4, and thus a leakage about the bolts is pre- 85 vented.

When the invention is applied to a silo, the latter ordinarily is provided with a doorway indicated by the reference character 7. Located within the silo 1 and disposed below the ring 2 is a band 6. As clearly shown in Fig. 3 the band 6 is divided so that it does not extend across the doorway 7, and bolts 8 or the like are employed 95 for attaching the ends of the band 6 to the wall of the silo 1 upon either side of the doorway 7.

Oppositely disposed lower holding devices pass through the wall of the silo 1 and are 100 connected with the band 6. These lower holding devices may be eye bolts 9 carrying nuts 10 and washers 11, as hereinbefore described in connection with the eye bolts 3. In the present embodiment of the invention, 105 the eye bolts 9 are 90 degrees remote from the oppositely disposed eye bolts 3.

Secured in the ground about the silo 1 are anchors 12, 14, 15 and 16. These anchors may be of any desired form and in the 110 present instance they are shown, each, as comprising a turn buckle 17 terminating in

an eye 18, different reference characters being applied to the anchors merely for the purpose of facilitating the description of the invention.

5 The means whereby the silo 1 is guyed and contained in an upright position comprises a pair of flexible elements. One of the flexible elements is secured at one end, as shown at 19, to the eye 18 of the anchor 12. Thence, the flexible element under consideration is extended upwardly as shown at 20 and is passed through one of the eye bolts 9. From the eye bolt 9, the flexible element is extended downwardly as shown at 21 and is prolonged, as shown at 22, through the eye of the anchor 14. Thence, the flexible element is extended upwardly as shown at 23 and is passed through one eye of the bolt 3 as shown at 24. Beyond 10 the eye bolt 3 under consideration the flexible element is formed into a loop 25 extended circumferentially of the silo 1. The flexible element thence passes as shown at 26 through one eye of the opposite eye bolt 3 and is extended downwardly as shown at 27, the end of the part 27 being secured as shown at 28 in the eye 18 of the anchor 12.

One end of the other flexible element is secured as shown at 29 to the anchor 15 and 30 thence is extended upwardly as shown at 30 through the other eye bolt 9 as shown at 31. The flexible element passes downwardly as at 32 and through the anchor 16 as shown at 33, the flexible element being extended 35 upwardly as at 34 and being passed through the other eye bolt 3 as shown at 35. Thence, the flexible element is extended part way around the silo 1 in the form of a loop 36, the loop 36 projecting in an opposite direction from the loop 25. The flexible element passes through the oppositely disposed eye bolt 3 as shown at 37 and thence is extended downwardly as indicated at 38, into connection with anchor 15.

45 As is well understood by riggers, thimbles 39 may be employed, as shown in Fig. 6, at all points whereby the flexible elements are bent upon themselves, to the end that the flexible elements may be tightened up 50 properly through the action of the turn buckles 17.

It is to be observed that when the flexible elements are under stress, the loops 36 and 25 exert a constricting pressure upon the 55 silo 1. The upper reinforcing ring 2 not only serves as a place of attachment for the eye bolts 3, but as well acts to sustain the silo against this constricting pressure.

Briefly considered, the device disclosed in 60 this application comprises an upright structure such as the silo 1, upper holding devices 3, lower holding devices 9, anchors 12, 14, 15 and 16, a pair of flexible elements engaged with the upper holding devices 3 to 65 form oppositely projecting loops 25 and 36

extended circumferentially of the silo 1, each flexible element including a pair of depending bights 27-20 and 21-23 and an upright bight 21-20 therebetween, the upright bight being engaged with one of the lower holding devices 9, and the depending bights being engaged with certain of the anchors, such as 12 and 14.

Having thus described the invention, what is claimed as new is:

1. In a device of the class described, an upright structure; upper and lower holding devices thereon; anchors; a pair of flexible elements engaged with the upper holding devices to form oppositely projecting loops 80 extended circumferentially of the upright structure, each flexible element including a pair of depending bights and an upstanding bight therebetween, the upstanding bight being engaged with one of the lower holding devices and the depending bights being engaged with certain of the anchors.

2. In a device of the class described, an upright structure; supporting bands within the upright structure; upper and lower holding devices extended through the upright structure and connected with the bands; anchors; a pair of flexible elements engaged with the upper holding devices to form oppositely projecting loops 85 extended circumferentially of the upright structure, each flexible element including a pair of depending bights and an upstanding bight therebetween, the upstanding bight being engaged with one of the lower holding devices and the depending bights being engaged with certain of the anchors.

3. In a device of the class described, an upright structure; upper and lower holding devices thereon; anchors; a pair of flexible elements engaged with the upper holding devices to form oppositely projecting loops 95 extended circumferentially of the upright structure, each flexible element including a pair of depending bights and an upstanding bight therebetween, the upstanding bight being engaged with one of the lower holding devices and the depending bights being engaged with certain of the anchors.

4. In a device of the class described, an upright structure; upper and lower holding devices thereon; anchors; a pair of flexible elements engaged with the upper holding devices to form oppositely projecting loops 100 extended circumferentially of the upright structure, each flexible element including a pair of depending bights and an upstanding bight therebetween, the upstanding bight being engaged with one of the lower holding devices and the depending bights being engaged with certain of the anchors; and a reinforcing band within the 105 upright structure, the reinforcing band being aligned with the loops.

4. In a device of the class described, an upright structure; upper and lower holding devices thereon; anchors; a pair of flexible elements engaged with the upper holding devices to form oppositely projecting loops 110 extended circumferentially of the upright structure, each flexible element including a pair of depending bights and an upstanding bight therebetween, the upstanding bight being engaged with one of the lower holding devices and the depending bights being engaged with certain of the anchors; and a reinforcing band within the 115 upright structure, the reinforcing band being aligned with the loops.

120

125

ture, the band being alined with the loops, and the upper holding devices being connected to the band.

5. In a device of the class described, an upright structure; upper and lower holding devices thereon; anchors; and a pair of flexible elements, each of which is secured at one end to an anchor, each flexible element being then extended upwardly into engagement with one lower holding device, thence downwardly into engagement with another anchor, thence upwardly into engagement with an upper holding device, thence, in the 10 form of a loop, circumferentially of the

upright structure into engagement with the other upper holding device, thence downwardly and secured at its other end to the first specified anchor, the loops of the respective flexible elements extending in opposite directions circumferentially of the 15 upright structure.

In testimony that I claim the foregoing as my own, I have hereto affixed my signature in the presence of two witnesses.

WILLIAM E. SMALL.
